UNITED STATES PATENT OFFICE

LOUIS LALANNE, OF MARSEILLE, FRANCE

SCUTTLE PORT AND LIKE TIGHT-CLOSED WINDOW

Application filed March 7, 1929, Serial No. 345,046, and in France January 9, 1929.

The present invention relates to scuttle ports and like tight closed windows, and particularly to a tight closing device therefor, and is an improvement in or modification of 5 the invention forming the subject matter of my prior patent application No. 322,369 of 1928.

The object of the invention is to obtain a tight closure for scuttle ports and like tight 10 closed windows operating from the outside towards the inside, and also to ensure the tight closure of the said scuttle ports and like tight closed windows without employing any packed joint, whilst retaining the 15 advantages resulting from the operation thereof by means of screwed rings, which forms the characteristic feature of the subject of the aforesaid prior patent application.

20 The elimination of the packed joints renders it possible to produce a tight closing device, the construction and operation of which are simpler than is the case in the apparatus previously described.

25 Some preferred constructional forms according to the invention are illustrated by way of example in the accompanying drawings, in which:

Fig. 1 is a sectional elevation of the lower 30 part of a scuttle port closing from outside inwardly against rubber packed joints together with its operating members, in the closed position.

Fig. 2 is likewise a sectional elevation of 35 the lower part of the same scuttle port in the open position,

Fig. 3 is a sectional elevation of the device 40 employed for rendering a scuttle port tight closing without using any rubber or other packed joint.

Fig. 4 is a sectional elevation of the lower 45 part of a scuttle port in the position of tight closure obtained by the application of the device shown in Fig. 3 and

Fig. 5 shows a modification of the scuttle port shown in Fig. 3 in the open position.

Fig. 6 shows a further embodiment in section.

The tight closing and the opening of the 50 scuttle port shown in Figs. 1 and 2 is effected simply by the manipulation of a toothed wheel or pinion 11 which is in permanent engagement with teeth 10 provided on a cylindrical crown or ring 6 having a screw thread 55 5 engaging with a corresponding screw thread 34 cut in the movable ring 35 carrying the pane holder 8 of the scuttle port, which can be adjusted by turning freely on pivots 36 located diametrically opposite to one another, 60 one only of said pivots being shown in the drawings.

The movable ring 35 is hollowed out on one 65 of its peripheral surfaces so as to form a groove for the reception of a rubber joint 37 which ensures the tightness of the closure at the exterior, whilst a counter ring 38 is fixed on the framework of the scuttle port. This last named ring is also grooved for the reception of a joint 39 which ensures the tightness 70 of the closure at the interior.

A cover 40 having a tightening joint is 75 fixed by known means to the pane holder. The said cover is adapted to allow the scuttle port to be opened without the necessity for its removal. By turning the pane holder 8 shown in Fig. 1, 180° round its pivots 36, the cover 40 may protect the scuttle port on its sea side against rough seas.

The exterior surface of the pane holder 8 is 80 curved in accordance with the radius of curvature of the scuttle port in such manner as to ensure that by contacting with the surface of the ring 35 having the same curvature a tight closure of this movable part will be 85 obtained.

The actuation of this device is effected by 90 the rotation of the toothed wheel 11, which operates the ring 6, so that the latter through the medium of its screw thread 5 displaces the

movable ring 35 which carries with it in its movement the pane holder 8 of the scuttle port.

In this device the screw threads 34 are not cut as in the devices previously described.

The scuttle port will be opened or closed according to the direction of rotation of the wheel 11.

In the scuttle port device shown in Figs. 4 and 5 the rubber tightening joints have been entirely eliminated, a tight closure being obtained by direct contact of the pane holder with the corresponding surfaces.

The device employed in order to obtain this result is shown in Fig. 3.

The pane holder 8 (Figs. 3, 4 and 5) is provided on each one of its faces with grooves in such manner as to produce raised portions 41 of conical section similar to the section of a truncated conical screw thread. One of these conical portions enters a groove 42 of corresponding cross section cut in the framework 2 of the scuttle port, and the other one of the said portions enters into a groove 43 of the same cross section cut in the movable ring 44, the said ring having screw thread 45 engaging with a screw thread 5 cut in the ring 6, which is rotated by means of the teeth 10 permanently in engagement with the operating toothed wheel 11.

In order to allow of the movements necessary for effecting the opening and the closing of the scuttle port the pane holder 8 is arranged concentrically in the interior of a ring 46 into which it enters and with which it contacts with slight friction. The said ring 46 is carried on a circular support 47 rigid with the framework 2. The said support is transversely grooved so as to form a guide 48 into which a tenon member 49 passes, and serving at the same time as a guide for the ring 46.

When the scuttle port is in the closed position as shown in Fig. 4, it is only necessary in order to open it, to operate the one wheel 11. The said wheel on its rotation actuates the ring 6 through the medium of the teeth 10, whilst the said ring 6 through the medium of the screw thread 5 displaces the groove 43 cut on the ring 44, thus causing it to move out of contact with the pane holder 8. If the manipulation of the toothed wheel 11 is continued, the ring 44 likewise continues its movement in advance of the scuttle port which has the effect of bringing the stop 50 carried by the said ring into contact with the tenon member 49 rigid with the ring 46 carrying the pane holder 8. As soon as this occurs, the backward movement of the ring 44 causes a similar movement of the pane holder 8 thus allowing of the adjustment of the scuttle port by turning it about the pivot 36 rigid with the supporting ring 46. The position of maximum opening is indicated 65 in dotted lines in Fig. 5.

The fixing of the scuttle port in the desired open position may be effected in various ways, of which only two are indicated in the drawings. One method of effecting this (see Fig. 4) consists in tightening up the screw 51 against the pivot 36. The other method of effecting the desired result (see Fig. 5) consists in the manipulation of a right and left handed screw 52 acting on a sector 53 fixed on one of the pivots 36.

As in the case of the preceding device, it is easy to fit on this scuttle port a cover similar to that shown in Fig. 1.

The device described in which all packed joints are eliminated may be applied to all the constructional forms illustrated and described in my aforesaid prior application No. 322,369 of 1928.

The employment of the device according to the present invention, presents numerous advantages, of which the principal ones are:

Great simplification in the construction and operation of the scuttle ports, and the assurance of absolutely tight closure of the latter obtained by a simple and rapid rotation of the parts in contact, one of which may, if desired, be made of a metal having a different resistance from that of the other part on which the first named part bears.

The devices according to the invention can be applied to scuttle ports of all dimensions and to all similar classes of openings. It is to be understood that the constructional form according to the invention can be modified in a variety of ways.

In Fig. 6 the scuttle port is a slight modification of the scuttle ports shown in Figs. 4 and 5 with the difference that this modified embodiment enables one to put a protecting cover 40 on the inside of the scuttle port, a tightening joint 55 being provided for obtaining a tight closure between an edge 60 of the pane holder 8 and said cover 40, whilst a flange 56 is provided along the whole circumference of the cover 40, on which flange 56 a known means acts upon for fixing the cover onto the pane holder. This known means consists in a screw threaded ring 54 of Z-shaped cross section, to be screwed by hand onto the cover 40, thus pressing the joint 55 tight onto the edge 60 of the pane holder. A collar with inward projecting flange 58 serves as a guide for the screw threaded ring 54 during screwing and fastening of the cover or shutter 40.

By turning this pane holder 8 together with its shutter or cover 40 around its pivots 36 for 180 degrees i. e. half a turn, the same cover or shutter 40 comes to lie on the outside of the scuttle port thus protecting the latter on its sea side against rough seas and waves.

Claims:

1. In a tight closing device for scuttle ports and the like, the combination of a pane holder constituted by two co-axial rings, the inner one of them having an exterior lateral

surface curved in accordance with the radius of the inner lateral surface of the outer ring in such a manner as to ensure a tight closure between both rings, pivots connecting both 5 rings together and enabling the inner ring to oscillate, a projecting member with tenon on the outer circumference of the outer ring of the pane holder, a fixed frame work, a transversal guide for said projecting member 10 and tenon, a movable ring with nose for co-acting with said tenon, an actuating ring acting upon said movable ring, means for moving said actuating ring in such a manner as to axially displace said actuating ring and said 15 movable ring relatively to one another, the front side of the inner ring of the pane holder having a ring shaped tightening surface, and a second ring shaped tightening surface with the same diameter as the first one, in front 20 of same and carried by the frame work.

2. In a tight closing device for scuttle ports and the like, a fixed frame work with circular opening, a concentrically arranged tightening surface on said frame work, an 25 axially movable pane holder, a tightening surface on the front face of the pane holder, and a tightening surface on the back face of the latter, the tightening surface on the front face destined to coact with the tightening 30 ring of the frame work, a ring arranged concentrically to the pane holder and movable in axial direction, said movable ring provided with a concentrically arranged tightening surface destined to coact with the 35 tightening surface on the back face of the pane holder, and means for removing first the movable ring so as to quit the tight closure between the latter and the pane holder and then the pane holder away from the tightening 40 ring of the frame work.

3. A tight closing device for scuttle ports and the like tight closed windows, consisting in a fixed frame work with a circular opening, a concentrically arranged tightening groove on said frame work, an axially 45 movable pane holder, grooves on each one of the faces of the pane holder in such a manner as to produce raised portions of conical section, the raised portion on the front 50 side destined to coact with the tightening groove of the frame work, a ring concentrically arranged relatively to the pane holder and movable in axial direction, said movable ring provided with a concentrically arranged 55 tightening groove and destined to coact with the raised portion on the back side of the pane holder, and means for shifting the pane holder and the movable ring relatively to the frame work so as to remove the movable ring 60 and to quit the tight closure between the latter and the pane holder and then to remove the pane holder away from the tightening groove of the frame work.

4. A tight closing device for scuttle ports 65 and the like tight closed windows, consist-

ing in a fixed frame work with a circular opening, a concentrically arranged tightening groove on said frame work, an axially movable pane holder, grooves on each one of the faces of the pane holder in such a manner 70 as to produce raised portions of conical section, the raised portion on the front side destined to coact with the tightening groove of the frame work, a ring concentrically arranged relatively to the pane holder and movable in axial direction, said movable ring provided with a concentrically arranged tightening groove and destined to coact with the raised portion on the back side of the pane 75 holder, means for shifting the pane holder and the movable ring relatively to the frame work so as to remove the movable ring and to quit the tight closure between the latter and the pane holder and then to remove the pane holder away from the tightening groove of 80 the frame work, the said pane holder constituted by two co-axial rings, the inner one of them having an exterior lateral surface curved in accordance with the radius of the inner lateral surface of the outer ring in such 85 a manner as to ensure a tight closure between both rings, pivots connecting both rings together and enabling the inner ring to oscillate, and means for fixing of the inner ring of the pane holder in the desired open or 90 closed position.

5. In a tight closing device for scuttle ports and the like, the combination of: a pane holder constituted by two co-axial rings; pivots connecting said co-axial rings together and enabling the inner ring to oscillate; a tenon on the outer ring of said pane holder; a fixed frame work; a transversal guide for the tenon on the outer ring of the pane holder; a movable ring having a nose 100 co-acting with said tenon member; an actuating ring acting upon the movable ring; means for moving said actuating ring in such a manner that an axial displacement of said actuating ring and said movable ring relatively to one another may be obtained; the inner ring of the pane holder having at least one ring-shaped tightening surface; and a second ring-shaped tightening surface having 105 the same diameter as the first one, in front of the latter and carried by the frame work.

6. A tight closing device for scuttle ports and the like tight closed windows, comprising in combination: a fixed frame work having a circular opening; a concentrically arranged tightening surface on said frame work; an axially movable pane holder constituted by two co-axial rings, the inner one of which is pivoted on the outer one; a tightening surface arranged on the front face of the inner ring of said pane holder and adapted to co-act with said first-named tightening surface; an axially movable ring arranged concentrically around the outer ring of said pane holder and provided on its outer 110 115 120 125 130

periphery with a screw thread; a tightening surface on said movable ring; a tightening surface arranged on the rear face of the inner ring of said pane holder and adapted to co-act with the tightening surface of said movable ring; an actuating ring adapted to rotate on its axis and provided with a continuous internal screw thread which is in constant engagement with the screw thread of said movable ring; and means for rotating said actuating ring.

In testimony whereof I have affixed my signature.
